(57) **CLAIM**

The ornamental design for a hunting sight, as shown and described.

DESCRIPTION

FIG. 1 is a perspective top view of my new hunting sight; FIG. 2 is a top plan view of my new hunting sight;

FIG. 3 is a side elevational view of my new hunting sight taken from the right side of FIG. 2;

FIG. 4 is a bottom plan view of my new hunting sight;

FIG. 5 is a side elevational view of my new hunting sight taken from the left side of FIG. 2;

FIG. 6 is an end view of my new hunting sight; and,

FIG. 7 is an end view of my new hunting sight from the end opposite that of FIG. 6.

The broken line showing the circular features illustrated in FIG. 7, the radial pattern of rectangular elements and the semi-circular portion about the radial pattern of rectangular elements of one end of the sight in FIGS. 1-5, and the repeating pattern of angled cuts on the two adjustment knobs in FIGS. 1-5 and 7 are for the purpose of illustrating environmental structure and form no part of the claimed design.
